GEORGES E. HENRY, OF MANSFIELD, OHIO, ASSIGNOR TO THE OHIO BRASS COMPANY,
OF MANSFIELD, OHIO, A CORPORATION OF NEW JERSEY.

CONDUCTOR-SUPPORT.

1,367,599.

Specification of Letters Patent.

Patented Feb. 8, 1921.

Application filed June 19, 1920. Serial No. 390,150.

To all whom it may concern:

Be it known that I, GEORGES E. HENRY, a citizen of Switzerland, residing at Mansfield, in the county of Richland and State of Ohio, have invented certain new and useful Improvements in Conductor-Supports, of which the following is a specification.

My invention relates to a device for gripping and supporting conductors and is particularly adapted to supporting trolley wires from overhead supports or hangers.

The objects of my device are to produce a clamping and supporting member which can be economically manufactured, is simple in its construction and simple in its application; a device which can be secured tightly in relation to the overhead support or hanger and aline with the conductor to which it is attached without altering its close relation to the hanger; a device which after being installed upon the hanger and the conductor will permit free rotative movement of the conductor with respect to the hanger if there is such tendency upon the part of the conductor. Other objects will be apparent to those skilled in the art after further disclosures herein based upon my description and claims.

To the attainment of these ends and the accomplishment of other new and useful objects, as will appear, the invention consists in the features of novelty in the construction, combination and arrangement of the several parts herein more fully described and claimed and shown in the accompanying drawing illustrating the embodiment of the invention, and in which:

Figure 1 is a side view at elevation of my invention shown attached to a trolley wire and to an overhead hanger or support.

Fig. 2 is a section on the line 2—2 of Fig. 1 and shows the relation of the parts but gripping the trolley wire and secured in position on the hanger.

Fig. 3 is a section on the line 2—2 of Fig. 1 but shows the relation of the parts when my invention is unattached to an overhead hanger and is not in gripping relation with a trolley wire.

Fig. 4 is a section on the line 4—4 of Fig. 2.

Fig. 5 is a section on the line 5—5 of Fig. 3.

Fig. 6 is a section on the line 6—6 of Fig. 2 and shows the relation of driving lugs herein later described.

It will be apparent to those skilled in the art that modification may be made in the form of device shown and described herein and such modification will fall within the scope of my invention.

One form of my device and my preferred form comprises a pair of clamping elements 1—1 provided at their lower end with means for engaging and gripping a conductor 3 which I have shown as a trolley wire. The upper end of the gripping elements 1—1 is provided with lugs 4 which enter and engage a rotating element 5. At the lower portion of the lugs 4 a shoulder 6 is formed which is engaged by the lower edge 7 of the rotating element 5. In order to secure these members together the opening to the element 5 is formed with straight depending sides as shown by the dotted line and after the lugs 4 have been entered into proper position the lower dotted edge of the element 5 is swaged over, rolled or otherwise formed to close the opening partially and produce a shoulder 7 to engage the shoulder 6. This permits the clamping members 1—1 to have free rotation in the element 5 when the gripping elements do not engage a trolley wire and to have a partial relative rotation as will be fully explained later when the gripping elements 1 engage a trolley wire 3. The point of engagement of the elements 6 and 7 acts as a fulcrum point for the gripping elements 1.

Upon the rotating element 5 is an inwardly depending annular flange 8 and when viewed on the line 4—4 of Fig. 2 the flange 8 is seen to have an elliptical section as shown in Fig. 4. The object of this elliptical construction is to provide means for engaging the lugs 4 when the gripping elements 1 are in position upon the trolley wire 3 and to move the lugs 4 outwardly and thereby throw the jaws 2 of the gripping elements 1 into a gripping or holding relation upon the trolley wire. This engagement of the elliptical flange 8 with the lugs 4 is brought about by rotating the element 5 relatively to the gripping members 1 when the gripping members are in engagement with the trolley wire. When there is no engagement between the gripping members 1 and the trolley wire there is sufficient clearance between the lugs 4 and the elliptical flange 8 to permit free and complete rotation of these elements relatively to each other.

The upper inner edge of the rotatable member 5 is shown as beveled as indicated by the numeral 9 but the continuity of this beveled surface is broken by lug 10 forming 5 an integral part of the rotatable member 5.

To properly support the device from an overhead hanger I secure to the rotatable member 5 a supporting member 11. In order to prevent the disengagement of elements 5 and 11, I roll, or swage over the lower edge 12 of the supporting member which is normally cast straight as indicated by the dotted lines. As the fit between the parts 5 and 11 is sufficiently loose to permit 10 relative rotation of the parts, I provide a lug 13 integrally secured to the member 11 which engages with the lug 10 of the rotatable member when the members 5 and 11 are rotated a sufficient amount in either direction. The engagement of the lugs 10 and 13 permits rotating the supporting member 11 by means of the rotatable member 5 which is provided on its exterior with means for the application of a wrench, into engagement 15 with an overhead hanger or support H. These hangers are usually provided with a depending stud 14 and therefore I provide the supporting member 11 with a threaded recess 15 adapted to engage the stud 14. In 20 order to disengage the supporting member from the hanger it is only necessary to rotate the element 5 in the reverse direction until the lug 10 engages the opposite side of the lug 13 whereby continued rotation of the 25 member 5 will cause the supporting member 11 to rotate in a reverse direction and disengage itself from the hanger.

In order to install my device upon a hanger and trolley wire, assuming that the 30 hanger and trolley wire have been positioned relatively to each other, I first secure the hanger by placing the threaded recess 15 in contact with the end of the stud 14 and then rotate the member 5 in the proper direction 35 until the lug 10 engages the lug 13 on the supporting member 11 and continued rotation of the rotatable member 5 will cause the supporting member 11 to be rotated and thread itself upon the stud 14 and this rotation of the members is continued until the 40 upper face of the supporting member 11 securely engages the lower face of the hanger H. It will probably be found that the clamping members 1 do not at this time align 45 with the trolley wire 3 but as the clamping members 1 are freely rotatable relatively to the other parts of the device as before explained, it is only necessary to rotate the clamping members 1 until they align with the 50 trolley wire and to then place the jaws 2 in proper engagement with the wire 3. Or the clamping members 1 and rotatable member 5 may be rotated in unison if desired until the clamping members 1 align with the 55

trolley wire 3. If at the time of engaging 60 the clamping members 1 with the trolley wire the lugs 4 should be engaged with the long diameter of the elliptical flange 8 as shown in Fig. 4, it will of course be necessary to change this relation of parts which is very 65 easily done by rotating the element 1 relatively to the element 5 until their relation is such as indicated in Fig. 5; that is where the short diameter of the elliptical member 8 70 engages with the lug 4.

Having engaged the device with the hanger and the clamping members 1 with the wire in order to cause the clamping members 1 to securely grip the trolley wire it is only necessary to rotate the element 5 in 75 either direction not to exceed a quarter revolution and the long diameter of the elliptical flange 8 will engage with the lug 4 and throw the lugs 4 away from each other and the jaws 2 toward each other and into firm 80 engagement with the trolley wire 3.

The gripping members 1 and rotatable member 5 will now be locked together and since the rotatable member 5 and supporting member 11 are free to rotate on account of disengagement of the lugs 10 and 13, the members 1 and 5 as a unit will be free to rotate relatively to the supporting member 11 or hanger H an amount which the clearance 85 between the lugs 10 and 13 will permit. This is a feature which will permit slight twisting of the trolley wire without necessity of loosening the device from the hanger which would be the case if the member 11 90 and members 1 were relatively non-rotatable.

In order to disengage the device from a trolley wire or hanger it is only necessary to rotate the element 5 a quarter turn to disengage the elliptical flange 8 from the lug 4 which will permit the trolley wire to be released from the gripping members 1 and then to rotate the element 5 in a reverse direction from that used to install the device 105 110 and until the lug 10 engages with the lug 13 when continued rotation will cause the supporting member 11 to be released and unscrewed from the stud 14.

In this application I have shown and described my preferred form of construction embodying my invention but this is only one of the many modifications which can be made in my invention and apparent to those skilled in the art and I do not wish to be 115 limited in the scope of my invention other than that set forth in the following claims.

Claims—

1. A wire support comprising a supporting member provided with means for attachment to a hanger, a rotatable member secured to the supporting member, means for limiting the amount of said rotation and

- gripping means rotatably secured to the rotatable member and adapted to engage and hold a wire.
2. A wire support comprising a supporting member provided with means for attachment to a hanger, a rotatable member secured to the supporting member, means for limiting the amount of said rotation, a pair of clamping members rotatably secured to the rotatable member and adapted to grip and hold a wire and means for moving the clamping members into engagement with the wire.
3. A wire support comprising a supporting member provided with means for attachment to a hanger, a rotatable member secured to the supporting member, means for limiting the amount of said rotation, gripping means secured to the rotatable member adapted to engage and hold a wire and a cam adapted to engage and move the gripping means into holding engagement with the wire when rotated.
4. A wire support comprising a supporting member provided with means for attachment to a hanger, a rotatable member secured to the supporting member, means on each of the above elements adapted to coact and limit the amount of said relative rotation and gripping means rotatably secured to the rotatable member and adapted to engage and hold a wire.
5. A wire support comprising a supporting member provided with means for attachment to a hanger, a rotatable member secured to the supporting member, means on each of the above elements adapted to coact and limit the amount of said relative rotation, gripping means rotatably secured to the rotatable member and adapted to engage and hold a wire and operating means on the rotatable member to engage and move the gripping means into holding engagement with the wire.
6. A wire support comprising a supporting member provided with means for attachment to a hanger, a gripping member to engage and hold a wire, and connecting means interposed between the above members to secure them together, the connecting means having limited relative rotation with respect to the supporting member and free relative rotation with respect to the gripping member.
7. A wire support comprising a supporting member provided with means for attachment to a hanger, a gripping member to engage and hold a wire, means connecting the above members and having limited rotation relative to the supporting member and free rotation relative to the gripping member and means for moving the gripping member into holding engagement with the wire and simultaneously locking the connecting means and gripping member against
- rotation but permitting the limited relative rotation of the supporting and gripping members to continue.
8. A wire support to grip and support a conductor comprising three relative rotatable members, a supporting member, a gripping member and a connecting member, the supporting member having means to engage a hanger, the connecting member having limited relative rotation with respect to the supporting member and having means to engage means on the supporting member to define said relative rotation in either direction, the gripping member having free relative rotation with respect to the connecting member when the gripping member is free of the conductor but non-rotatable relatively to the connecting member when engaging the conductor and means for causing said non-rotation and secure engagement of the gripping member to the conductor.
9. A wire support comprising a supporting member provided with means for attachment to a hanger, means having a limited relative rotation to the supporting member and engaging the same for rotating the supporting member into engagement with the hanger, and gripping means adapted to hold a wire and having free relative rotation with respect to the above mentioned means.
10. A wire support comprising a supporting member provided with means for attachment to a hanger, means having a limited relative rotation to the supporting member and engaging the same for rotating the supporting member into engagement with the hanger, gripping means adapted to hold a wire and having free relative rotation with respect to the above mentioned means, and operating means adapted to move the gripping means into a holding engagement with the wire and lock the gripping means against rotation relatively to the second named means but permitting relative rotation with respect to the supporting member.
11. A wire support comprising a supporting member provided with means for attachment to a hanger, means having a limited relative rotation with respect to the supporting member and engaging the same for rotating the same into engagement with the hanger, a gripping means adapted to hold a wire and having free relative rotation with respect to the above mentioned means and means to move the gripping means into holding relation to the wire.
12. A wire support comprising a supporting member provided with means for attachment to a hanger, gripping means adapted to engage and hold a wire, a connecting member for uniting the above elements, the connecting means adapted to rotate the supporting member into engage-

ment with a hanger when rotated in one direction and to have a free but limited rotation relative to the supporting member when rotated in the reverse direction, means 5 on the connecting member adapted to move the gripping means into a holding relation with the wire when the connecting member is rotated in a reverse direction but releasing said grip on the wire when the connecting member is rotated in the opposite 10 direction.

13. A wire support comprising a supporting member provided with means for attachment to a hanger, gripping members 15 adapted to engage and hold a wire, means connecting the members in a relative rotative relation to each other and means adjustably rotatable to engage the gripping

members to move the gripping members into engagement with the wire. 20

14. A wire support comprising a supporting member provided with means for attachment to a hanger, a rotatable member provided with means engaging a supporting member to cause the supporting member to 25 rotate in unison with the rotatable member but permitting a limited relative reverse rotation of the rotatable member, means for securing the above members together, gripping means adapted to engage and hold a 30 wire, means for securing the rotatable member and gripping means together and means to move the gripping means into holding engagement with the wire.

In testimony whereof I affix my signature. 35
GEORGES E. HENRY.
